UNITED STATES PATENT OFFICE

NICHOLAS P. COURTNEY, OF PASSAIC, NEW JERSEY

RECEPTACLE OPENER

Application filed July 16, 1930. Serial No. 468,381.

The present invention relates generally to cans, drums and canisters and more particularly to means for opening the lids thereof and the object of the invention is to provide a device which is to be sold as part of the receptacle and designed for prying off the lid and which is extremely simple in its construction, inexpensive to manufacture, easy to manipulate, and thoroughly efficient and reliable in use.

My device is attached to the receptacle and located on the cover thereof and is so constructed as to permit its being folded onto the top of the receptacle and not interfere with the stacking of receptacles so equipped.

Another important provision of the invention lies in the ability of the device to reopen the receptacle time after time without renewal of the parts, and also the cover of the receptacle may be replaced to its original tightness without removing the device from the cover.

With the above and numerous other objects in view as will appear as the description proceeds, the invention resides in certain novel features of construction, and in the combination and arrangement of parts as will be hereinafter more fully described and claimed.

In the drawings the eight figures are all perspective views of different embodiments of the opening means in position after having pried open the lid.

Referring to the drawings in detail and first to Figure 1 it will be seen that A denotes the can and B the lid. The lid is formed with a bead 5 of continuous formation except for a space 6. The letter C denotes generally the opener which is formed from a single strand of metal bent over upon itself intermediate its ends and twisted to provide a shank 7 with arms 8 extending therefrom and having angular extensions 9 over upon themselves terminating in oppositely directed trunnions 10 which are journaled in the ends of the bead 5. The shank normally lies over upon the lid B as designated in dotted lines in Figure 1 and by swinging the shank up to an upright position it will

be seen that the lid B will be pried to an open position.

In Figure 2 the construction is practically the same except a different shaped can is illustrated. In Figure 3 the construction is practically the same except that the lid B has the bead 5a at its bottom rather than at the top and extensions 11 are disposed at right angles to the portions 9a to be interposed between said portions 9a and the trunnions 10a. The embodiment in Figure 4 is practically the same except that portions of the bead are offset inwardly as indicated at 5c. The construction in Figure 5 is the same except that portions 9d are in the same plane with each other and with the portions of the arms 8d.

In Figure 6 the letter Ae denotes the can and the letter Be denotes the lid having the bead 5e with spaced ends 6e. The opener Ce is formed from a single strand of material bent over upon itself and shaped to provide a shank 7e one end of which terminates in a trunnion 10e while the other end thereof is extended and coiled about a portion of the bead 15 of the can as is indicated at 16 and then is extended back as at 17 and terminates in another trunnion 10e.

In Figure 7 the device Cb is formed from a single strand of metal bent over upon itself and shaped to provide a shank 7b having arms with an ogee formation 18 which terminates in trunnions 10b journaled in the ends of the bead 19 of the can Ab so that a portion of the ogee extension 18 may be caught under the bead 5b of the lid Bb for prying the same open.

In Figure 8 the device Cg is formed from a single strand of material bent over upon itself and shaped to provide a shank 7g having parallel arms 8g extending therefrom with curved intermediate portions 20 for engaging the bead 21 of the can Ag and these arms 8g terminate in trunnions 10g journaled in the end portions 6g of the bead 5g of the lid Bg.

It is thought that the construction, operation, utility and advantages of this invention will now be clearly understood without a more detailed description thereof. The numerous embodiments of the invention illustrated have been shown merely for the pur-

poses of exemplification since in actual practice they attain the features of advantages enumerated as desirable in the statement of the invention and the above description and it is to be understood that changes in details of construction may be resorted to without departing from the spirit and scope of the invention as hereinafter claimed or sacrificing any of its advantages.

10 Having thus described my invention, what I claim as new is:—

15 1. In combination, a receptacle member, a lid member, one of said members having a bead a portion of which has an opening thereby forming a pair of opposed spaced ends, and an opening device extending between said spaced ends and having trunnions projecting away from each other and journaled in said spaced ends of the bead.

20 2. In combination, a receptacle member, a lid member, one of said members having a bead a portion of which has an opening thereby forming a pair of opposed spaced ends, and an opening device extending between said spaced ends and having trunnions projecting away from each other and journaled in said spaced ends of the bead, said opening device being formed of a single piece of metal bent over upon itself and twisted about itself and terminating in said trunnions.

In testimony whereof, I affix my signature.

NICHOLAS P. COURTNEY.
